UNITED STATES PATENT OFFICE.

WALTER W. DECKER, OF MINNEAPOLIS, MINNESOTA.

SLIDING-DOOR FASTENER.

1,128,420.

Specification of Letters Patent. Patented Feb. 16, 1915.

Application filed May 8, 1914. Serial No. 837,100.

To all whom it may concern:

Be it known that I, WALTER W. DECKER, a citizen of the United States, residing at Minneapolis, in the county of Hennepin and 5 State of Minnesota, have invented certain new and useful Improvements in Sliding-Door Fasteners; and I do hereby declare the following to be a full, clear, and exact description of the invention, such as will enable others skilled in the art to which it 10 pertains to make and use the same.

My invention has for its object to provide an improved lock for the sliding side doors of box cars; and, to such ends, generally 15 stated, the invention consists of the novel devices and combinations of devices herein-after described and defined in the claims. It is a well-known fact that these side doors of box cars, when unlocked, are free to slide 20 back and forth, so that, under bumping actions of the cars, the doors will be thrown violently against their stops and produce a pounding action, which in a short time tears loose or very greatly damages the door stops, 25 and also damages the doors themselves. When an attempt is made to lock or fasten these doors either at top or bottom, the momentum of the doors, under bumping actions, tilts the doors and produces an upward or downward pounding action on the 30 door-supporting rails.

My improved lock will not only lock the door in a closed position, but will serve to lock or secure the door either entirely open 35 or partly open, and resist the inertia of the door from the center of gravity thereof, so that the door will not be oscillated under bumping strains.

In the accompanying drawings, which 40 illustrate the invention, like characters indicate like parts throughout the several views.

Referring to the drawings, Figure 1 is a side elevation, with some parts broken away, showing the body of a box car and illustrating 45 my improved lock applied to one of the side doors thereof; Fig. 2 is a vertical section taken on the line $x^2 x^2$ of Fig. 1; Fig. 3 is a horizontal section taken approximately on the line $x^3 x^3$ of Fig. 1; Fig. 4 is a detail in 50 section on the line $x^4 x^4$ of Fig. 1; and Fig. 5 is a detail in elevation, showing the head of the lock device removed from working position.

The numeral 1 indicates the body, and the 55 numeral 2 one of the side doors of a box car. This door 2, as shown, is provided with

hanger brackets 3 equipped with rollers 4 that run on the customary overhead door-supporting rail 5, so that the door is mounted to slide in the usual way. The lower edge 60 of the door is held against lateral outward swinging movement by the usual guide lugs 6 and 7, and when the door is closed, it bears against the usual stop strip 8 secured on the side of the car.

In accordance with my invention, a horizontally disposed lock bar 9 is rigidly secured, at one end, to the side of the car, as shown, by means of anchor bracket 10. This lock bar may be made in various different forms, but, as shown and preferred, is in the form of a channel iron having, in its lower flange, a plurality of longitudinally spaced perforations 11. Rigidly secured on the car door and embracing the projecting end of the lock bar 9, is a so-called lock head 12, that is adapted to slide on the side bar when the door is moved. This lock head 12 is provided with a depending hub 13, through which works an upwardly sprung 80 pressed lock bolt 14, the upper end of which is adapted to engage any one of the perforations 11 of the lock bar 9. The perforations 11 are so disposed that the lock bolt 14 will engage therewith to lock the door either in a 85 closed position or in a completely opened position, in any one of several intermediate positions. With this arrangement, as is evident, the door may be locked and held against sliding movements in any of the 90 several positions noted, so that it is thereby prevented from making any initial movement and, hence, from acquiring any pounding momentum under bumping actions of the cars. Furthermore, as the said bar 9 is 95 locked on the horizontal line that intersects or approximately intersects the center of gravity of the door, there will be no tendency to rock the door on its supports, when cars are bumped together. As shown, the 100 door 2 is also provided with a channel-shaped casing 15, preferably of sheet metal, aligned with the lock head 12, into which the lock bar 9 is adapted to be telescoped when the door is moved into an open position.

As an efficient means of sealing the car, with the door either in a closed or partly opened position, a secondary lock bolt 16 is passed through co-incident perforations in the primary lock bolt 14 and in the hub 13 105 of the lock head. This secondary bolt 14, at its projecting end, has a slit or elongated

perforation 17, through which the seal is adapted to be passed.

The above described lock device, of course, dispenses with the original hasp and lock usually employed in connection with car doors of the above noted character.

What I claim is:—

1. The combination with a car body and a door slidably mounted thereon, of a lock device comprising a lock bar secured to one of the members, at one end, extending in the direction of the travel of the door, and arranged to permit said door to slide between said car body and lock bar and a lock head secured on the other of said members and slidably on said lock bar, and means for locking together said bar and head, to secure the said door in different positions.
2. The combination with a car body and a door slidably mounted thereon, of a lock device comprising a lock bar secured to one of the members, at one end, extending in the direction of the travel of the door, and arranged to permit said door to slide between said car body and lock bar and a lock head secured on the other of said members and slidably on said lock bar, and means for locking together said bar and head, to secure the said door in different positions, the said lock bar being extended on a line that approximately intersects the center of gravity of said door.
3. The combination with a car body and a door mounted for horizontal sliding movements thereon, of a horizontal lock bar secured to said car body, at one end, and arranged to permit said door to slide between said car body and lock bar and a lock head secured to said door and slidable on said lock bar, and provided with a lock bolt engageable with perforations on said lock bar, to secure said door in different positions.
4. The combination with a car body and a door mounted for horizontal sliding movements thereon, of a horizontal lock bar secured to said car body, at one end, and ar-

ranged to permit said door to slide between said car body and lock bar, a lock head secured to said door and slidable on said lock bar, and provided with a lock bolt engageable with perforations on said lock bar, to secure said door in different positions, and a channel-shaped plunger casing secured to said door and alined with said lock head, into which said lock bar is adapted to be telescoped when the door is moved into an opened position.

5. The combination with a car body and a door mounted for horizontal sliding movements thereon, of a horizontal lock bar secured to said car body, at one end, and arranged to permit said door to slide between said car body and lock bar, a lock head secured to said door and slidable on said lock bar, said lock bar having longitudinally spaced perforations, a lock bolt mounted in said lock head and engageable with said perforations, and a second lock bolt serving to lock the first noted bolt against movements in respect to said lock head.

6. The combination with a car body and a door mounted for horizontal sliding movements thereon, of a horizontal lock bar secured to said car body, at one end, and arranged to permit said door to slide between said car body and lock bar, a lock head secured to said door and slidable on said lock bar, said lock bar having longitudinally spaced perforations, a lock bolt mounted in said lock head and engageable with said perforations, and a second lock bolt serving to lock the first noted bolt against movements in respect to said lock head, the said second lock bolt having a projecting perforated end, through which a car seal may be inserted.

In testimony whereof I affix my signature in presence of two witnesses.

WALTER W. DECKER.
